(57) **CLAIM**

The ornamental design for a tyre tread, as shown and described.

DESCRIPTION

FIG. 1 is a perspective view of the tyre tread of the present invention;

FIG. 2 is a front view thereof;

FIG. 3 is a side view thereof;

FIG. 4 is a front view of another embodiment thereof;

FIG. 5 is an enlarged front view; and,

FIG. 6 is an enlarged side view.

In the drawings, the broken lines depict portions of a tyre that forms no part of the claimed design.
